CLAIM

The ornamental design for a fender panel for automobiles, as shown and described.

DESCRIPTION

FIG. 1 is a perspective view of the fender panel for automobiles according to the present invention.

FIG. 2 is a front view of the fender panel for automobiles of FIG. 1.

FIG. 3 is a rear view of the fender panel for automobiles of FIG. 1.

FIG. 4 is a left side view of the fender panel for automobiles of FIG. 1.

FIG. 5 is a right side view of the fender panel for automobiles of FIG. 1.

FIG. 6 is a top view of the fender panel for automobiles of FIG. 1; and,

(Continued)

FIG. 7 is a bottom view of the fender panel for automobiles of FIG. 1.

1 Claim, 7 Drawing Sheets
